UNITED STATES PATENT OFFICE.

JOHN M. TUCKER AND JAMES ARMSTRONG WILDING, OF LONDON, ENGLAND.

CARBURETER.

1,106,258.

Specification of Letters Patent.

Patented Aug. 4, 1914.

Application filed November 1, 1913. Serial No. 798,754.

To all whom it may concern:

Be it known that we, JOHN MICHAEL TUCKER and JAMES ARMSTRONG WILDING, subjects of the King of Great Britain, residing at London, England, have invented new and useful Improvements in or Relating to Carbureters for Internal-Combustion Engines, of which the following is a specification.

10 This invention relates to carbureters for internal combustion engines, and the object of the said invention is to provide a construction or carbureter comprising improved means for breaking up or atomizing the jet 15 or jets of liquid fuel as the latter leaves the orifice or orifices through which it is admitted into the vaporizing or mixing chamber.

The improved carbureter comprises a 20 member having formed therein an orifice or orifices through which the liquid fuel is introduced into the vaporizing or mixing chamber, in combination with a member provided with a grating, grid, or one or more 25 blades arranged in proximity to the said orifices, and means for supporting said members and rotating one or both of them to effect a relative rotation of the grating, grid, blade or blades, in front of and past 30 the said orifice or orifices, the said grating, grid, blade or blades being essentially arranged to move edgewise transversely to the jet or jets emerging from the said orifice or orifices, in order to intermittently cut 35 through and divide the jet or jets of liquid fuel as the latter enters the vaporizing or mixing chamber before it is mixed with the air passing through the carbureter. The rotation of one or both of the said members is preferably effected by a fan which is 40 driven in the known manner by the air current passing through the carbureter, but such movement may be effected by any other suitable means.

45 The accompanying drawings show how the said invention may be conveniently and advantageously carried into practice.

In these drawings:—Figure 1 shows in central section, a carbureter constructed according to the present invention. Fig. 2 shows a section taken on the line X—X, Fig. 1. Fig. 3 is a view similar to Fig. 1 illustrating a modified arrangement. Fig. 4 is a detail view showing in central section 50 a modified arrangement of jet orifice hereinafter referred to. Fig. 5 is a partial cen-

tral section of a carbureter illustrating a modified constructional form.

As shown in Figs. 1 and 2, *a* is a vaporizing or mixing chamber into which air is admitted through orifices *b* under the control of a valve *c* in the well-known manner. A liquid fuel supply pipe *d* communicates with an annular conduit *e* arranged around the interior of the chamber *a* and opening into the same through jet orifices *f*. A fan *g* rotatably supported on a suitable anti-friction bearing is arranged in the part of the chamber *a* through which the air current passes, and the ends of the vanes of this fan carry blades *h* which by the movement of the fan are carried past the orifices *f* to intermittently cut through and divide the jets of liquid fuel as the latter enters the vaporizing chamber through the several stationary orifices *f*.

As shown in Fig. 5, the fan may be constructed with vanes *m* rotatably mounted on arms *n* projecting from a hub *o* carrying the blades *h* set edgewise transversely to the jets emerging from the orifices *f*. By turning these vanes about their respective axes the velocity of rotation of the fan in reference to the velocity of the air can be varied so that sufficient atomization may be insured with slow engine speeds or slow air velocity without necessitating unduly high speeds of the fan when the engine is running at normal speeds or when the air velocity is high. The adjustment of the angle of the vanes in accordance with the required variation in the speed of the fan may be effected by centrifugal or other automatic controlling means, and to this end the vanes *m* may be arranged on a sleeve *p* having a quick threaded screw-nut portion *q* engaging a screw threaded portion *r* on the arm *n*. The sleeve is thrust outwardly by a spring *s*. At the outer end of the arm *n* a block *t* with lugs *u* is secured by a pin *v*. A weighted lever *w* pivoted between the lugs *u* on a pin *x* has one end *y* resting against the sleeve *p* at the outer end thereof. When the speed of the fan increases the weighted end *z* of the lever *w* moves outwardly so that the end *y* of the lever thrusts the sleeve *p* inwardly against the thrust of the spring *s*. As the sleeve moves longitudinally on the arm *n* it is rotated by the interengaged screw threaded parts *q*, *r*, thus varying the angle at which the vanes are set with respect to the direction of the current of air impinging thereon.

As the speed of the fan decreases the parts are restored to their initial positions by the thrust of the spring *s*.

Referring to Fig. 3, the liquid fuel supply pipe *d'* is formed with a rotatable upper portion comprising radially arranged tubular arms *i* through which the liquid fuel passes to orifices *f'* opening into the vaporizing or mixing chamber *a'*. The arms *i* carry vanes *j* forming a fan by which the current of air through the chamber *a'* is utilized to rotate the arms *i*. Blades *k* are supported stationarily in proximity to the orifices *f'*.

15 The horizontal arrangement of the jet orifice as shown in Figs. 1 and 2, is to some degree defective in that when the carbureter is tilted, for example, when the carbureter is employed on an engine mounted on 20 an automobile vehicle and the latter is ascending or descending a hill, it may happen that the liquid fuel pours through the jet orifice by gravitation independently of suction induced by the movement of the engine's piston. In the arrangement shown in 25 Fig. 4, the jet orifice *f²* is inclined upwardly from the conduit *e* to the chamber *a*. With this arrangement the carbureter can be tilted to a considerable angle without the liquid 30 fuel flowing out by gravitation.

What we claim is:

1. In a carbureter, a member having a jet orifice formed therein through which fuel is

supplied into the air conduit through the carbureter, a blade which when in proximity 35 to the outlet from said orifice is set edgewise transversely to a jet emerging from the said orifice, and means distinguished from the said blade and adapted to cause relative rotational movement between the said orificed 40 member and the said blade.

2. In a carbureter, a member having a jet orifice formed therein through which fuel is supplied into the air conduit through the carbureter, a blade which when in proximity 45 to the outlet from said orifice is set edgewise transversely to a jet emerging from the said orifice, and a fan adapted to cause relative rotational movement between the said orificed member and the said blade. 50

3. In a carbureter a member having a fuel supply orifice formed therein so as to direct a jet issuing therefrom at an angle to a given plane, a blade which when in proximity to the outlet from the said orifice is set edgewise transversely to the said jet, and means distinguished from the said blade and adapted to cause relative rotational movement of the said orificed member and the 55 said blade about an axis normal to the said plane.

JOHN M. TUCKER.
JAMES ARMSTRONG WILDING.
